BOTTLE CARRIER

Filed July 6, 1928

INVENTOR

H. E. Watrous,

BY *Murphy & Leo*

ATTORNEY

UNITED STATES PATENT OFFICE.

HAROLD E. WATROUS, OF PORTLAND, OREGON.

BOTTLE CARRIER.

Application filed July 6, 1928. Serial No. 290,756.

This invention relates to a bottle carrier and is more particularly adapted for use in conveying milk bottles.

An object of the invention is the provision of a bottle carrier including a hand grip and a pair of spring pressed members pivotally mounted on the hand grip which are adapted to be forced over the top of the bottle and automatically grip the same for conveying purposes, the weight of the bottle in connection with the spring, serving to maintain the pivoted member in clamping position around the neck of the bottle.

This invention will be best understood from a consideration of the following detailed description in connection with the accompanying drawings; nevertheless, it is to be understood that the invention is not confined to the disclosure being susceptible of such changes and modifications as shall define no material departure from the salient features of the invention as expressed in the appended claims.

In the drawings:—

25 Figure 1 is a view in perspective of a bottle showing my invention applied thereto,

Figure 2 is a vertical section of the bottle carrier and bottle,

30 Figure 3 is a section taken along the line 3—3 of Fig. 2.

Referring more particularly to the drawings, 10 designates a bottle having a neck 11 and an annular bead 12, adjacent the neck forming a shoulder by which the bottle is supported upon the carrier as will be presently explained. The carrier consists of a curved handle 20 having its free ends straight, as shown at 21, to receive rivets 22 forming pintles for pivotally mounting 40 pairs of swinging bars 23 and 24. U-shaped springs 25 having central loops 26 are mounted on the pintles 22 in which project a pair of legs 27 having inturned portions 28 embracing an edge of a bar 23 or 24, and 45 received within a notch 29 in an edge of a swinging bar.

Secured to the bars 24 is a semi-circular member 30 having a projection provided with ears 31 secured to the bars 24. A second semi-circular member 32 is provided with ears 33 secured to the swinging bars 23. Each of the semi-circular members 30 and 32 have a flared lower edge 34 which will facilitate the application of the carrier to a 55 bottle. The upper edge of each semi-cir-

cular member, as shown at 35, is inturned so that it will snugly engage beneath the shoulder 12 of the bottle 10.

The operation of my device is as follows: The bars 22 and 23 are moved into close association with each other or in approximate alining relation by the springs 25, thereby retaining the curved members 30 and 32 in a uniform spaced relation. In order to insert the neck of the bottle through the bottle engaging members 30 and 32 these members are spread apart and the flared portions 34 are pressed down on the top of the bottle and when sufficient pressure has been exerted on the device the flared member 34 will aid in forcing the curved stops 30 and 32 apart for the insertion of the neck of the bottle. When the members 30 and 32 are released they will force the clamping member into engagement with the neck of the bottle by the spring member 35.

The upper edges 35 of the clamping members 30 and 32 will engage beneath the shoulder of the bead 12 and the bottle will be retained in the carrier. The weight of the 80 bottle and its contents will aid materially in maintaining the clamping members in operative relation with the bottle.

In order to release the carrier it is only necessary to force the clamping members 30 and 32 apart whence the neck and the bead 12 may be removed between the clamping members. It will be seen by such construction that the bottle carrier may be readily applied to a bottle and removed with very 90 little trouble.

I claim:—

1. A bottle carrier comprising a handle, a pair of bars pivotally mounted on each end of the handle, a spring for retaining each pair of bars in alining relation, bottle engaging members, each bottle engaging member having an end thereof connected to the free end of a bar of a pair of the bars. 95

2. A bottle carrier comprising a handle, a pair of bars pivotally mounted on each end of the handle, a spring for retaining each pair of bars in alining relation, bottle engaging members, each bottle engaging member having an end thereof connected to the free end of a bar of a pair of the bars, each bottle engaging member being formed of relatively stiff material. 100

3. A bottle carrier comprising a handle, a pair of bars pivotally mounted on each 110

- end of the handle, a spring for retaining each pair of bars in alining relation, bottle engaging members, each bottle engaging member having an end thereof connected 5 to the free end of a bar of a pair of the bars, each bottle engaging member being formed of relatively stiff material and provided with a flared flange for facilitating the application of the members to the bottle.
- 10 4. A bottle carrier comprising a handle, a pair of bars pivotally mounted on each end of the handle, a spring for retaining each pair of bars in alining relation, semi-circular strips of relatively stiff material 15 embracing opposite portions of a bottle, each end of a strip of relatively stiff mate-
- rial embracing opposite portions of a bottle, each end of a strip being secured to a bar of a pair.
5. A bottle carrier comprising a handle, 20 a pair of bars pivotally mounted on each end of the handle, a spring for retaining each pair of bars in alining relation, semi-circular strips of relatively stiff material embracing opposite portions of a bottle, 25 each end of a strip of relatively stiff material embracing opposite portions of a bottle, each end of a strip being secured to a bar of a pair, one edge of the strip being flared outwardly to facilitate the application of 30 the strips to the neck of a bottle.

HAROLD E. WATROUS.
